UNITED STATES PATENT OFFICE

PIERRE H. MEYER, OF NEW YORK, N. Y.

WEDGE DEVICE

Application filed June 28, 1930. Serial No. 464,458.

This invention relates to wedge devices for use in conjunction with what are known as shams for securing said shams firmly in position; and the object of the invention is to provide a device of the class specified in the form of an L-shaped body, one part of said body forming a finger piece, and the other part extending at right angles to the first named part and being wedge-shaped in form, and including a spring member folded backwardly upon the second named part and normally arranged in spaced relation thereto; a further object being to provide a wedge device of the class specified, the free end of the spring member of which is curved outwardly and fashioned to form a series of prongs or projecting members adapted to engage an adjacent body to retain the device against displacement with reference thereto; and with these and other objects in view, the invention consists in a device of the class and for the purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a plan view of a part of a counter showing a number of shams arranged thereon and illustrating a number of my improved wedge devices.

Fig. 2 is a partial section on the line 2—2 of Fig. 1.

Fig. 3 is a sectional, detail view of one of the wedge devices detached; and,

Fig. 4 is a side view of the device shown in Fig. 3.

To illustrate one method of carrying my invention into effect, I have shown in Figs. 1 and 2 of the drawings, a part of a counter 10 representing the table member of the counter, 11 an upstanding wall at one side of the counter, and 12 another wall arranged at the other side of the counter. At 13, I have shown shams, three of which are illustrated in Fig. 1, and one of which is shown in section in Fig. 2, said shams consisting of elongated

boards extending from one wall 11 to the wall 12, and being covered by suitable facings 14 which extend onto the side walls of the sham as indicated at 15. The facings 14 are usually composed of fibrous material, but 55 may be of any desired texture. At 16, I have shown a number of partition members consisting of strips of glass arranged between adjacent side edges of the shams 13, and extending from the wall 11 to the wall 12. At 60 17, I have shown other transverse partitions supported between opposed partitions 16 by suitable devices 18, it being understood that the partitions 17 rest upon the upper face of the arms 13 as clearly illustrated in Fig. 2 65 of the drawings.

In devices of the class described, it is commonly experienced that the length of the shams is not sufficient to fit snugly between the walls 11 and 12, and are thus capable of movement upon the table 10, which is often-times detrimental, in that such movement would, in many cases, upset and disarrange articles placed on display upon the sham.

To avoid this difficulty, I have produced a 75 very inexpensive and yet practical wedge device for securely retaining the shams against movement. Said devices are indicated at 19, in Figs. 1 and 2 of the drawings, one of said devices being arranged at one 80 end of each of the shams, and may be disposed at the front or outer side of the shelving or adjacent the wall 11 or adjacent the inner wall 12, as will be seen. The wedge devices are preferably fashioned from sheet 85 metal, fibre or similar material, folded to form a top finger piece 20 and a wedge portion 21 extending at right angles from the finger piece 20 and consisting of a straight wall 22 and an angularly disposed wall 23

formed integral with the wall 22 through the fold 24 and forming a spring member capable of flexure toward and from the wall 22. The free end 25 of the member 23 is flared outwardly as clearly seen in Fig. 3, 90 and fashioned to form a plurality of spaced projecting members 26, which are adapted to engage the facing 14 disposed on the walls of the sham 13 as seen at 15.

In the use of my improved device, after

- the sham has been placed in position, with the required number of partitions 16 in place, the wedge device is placed between one wall 11-12 and the adjacent wall of 5 the sham and forced downwardly into the position shown in Fig. 2, in which operation, the spring member 23 is compressed and the projecting members 26 are moved into firm engagement with the sham or its facing. 10 When in this position, the sham is held against accidental displacement upon the table 10. In removing the sham, the finger piece 20 may be used to raise the sham as well as the wedge engaging the same. It will be 15 understood that while the wedge devices are shown disposed at the narrow ends of the shams, that they may be employed along the sides thereof. However, the use at the ends is preferred in order not to interfere 20 with the articles placed on display.

While I have shown certain details of construction for carrying my invention into effect, it will be understood that I am not necessarily limited to these details, and various changes in and modifications of the construction herein shown and described, may be made within the scope of the appended claims, without departing from the spirit of my invention or sacrificing its advantages. 30 Having fully described my invention, what I claim as new and desire to secure by Letters Patent, is:

1. In a counter construction, a table member and oppositely disposed walls projecting 35 above the upper surface of the table member, a sham mounted on the table member and arranged between said walls, a wedge device adapted to be forced into position between one of said walls and the sham to retain said 40 sham against movement upon the table member, said device comprising a comparatively wide L-shaped body, one part of which is wedge-shaped in form and the other part being arranged at right angles to the first 45 named part and forming a finger piece, and said first named part involving two integral members, one of which has resilient properties and said resilient member terminating in an outwardly curved, serrated end. 50 2. A wedge device of the class described fashioned from a sheet of material, folded to form angularly disposed parts, one of said parts forming a finger piece and the other part including a spring member of less dimensions than its companion part and being movable relatively thereto, and said spring member terminating in a plurality of projecting prongs. 55

3. A wedge device of the class described 60 fashioned from a sheet of material, folded to form angularly disposed parts, one of said parts forming a finger piece and the other part including a spring member of less dimensions than its companion part and being movable relatively thereto, and said 65

spring member terminating in a plurality of projecting prongs offset with respect to the plane of said member.

4. A wedge device of the class described, comprising a V-shaped end portion, one part 70 of which has spring properties and being movable with respect to the other part, said last named part terminating in an angularly extending flange arranged over the spring part and in spaced relation thereto and forming a finger piece for said device, and said first named part terminating in an outwardly flared end. 75

In testimony that I claim the foregoing as my invention I have signed my name this 23rd day of June, 1930.
